DESIGN FOR A BOTTLE OR SIMILAR ARTICLE

Earle M. Cobb, Cutler, Calif., assignor to California Growers Wineries, Cutler, Calif., a co-operative marketing association of California

Application April 20, 1939, Serial No. 84,435

Term of patent 14 years

To all whom it may concern:

Be it known that I, Earle M. Cobb, a citizen of the United States, residing at Cutler, in the county of Tulare, State of California, have invented a new, original, and ornamental Design for a Bottle or Similar Article, of which the following is a specification, reference being had to the accompanying drawing, forming part thereof.

I claim:

The ornamental design for a bottle or similar article, as shown.

E. M. COBB.
